COSMETIC DISPENSER

Wayne M. Becker, Studio City, Calif., assignor to Derse Products, Inc., San Marino, Calif., a corporation of California

Filed May 25, 1959, Ser. No. 56,063

Term of patent 14 years

(Cl. D2—3)

FIG. 1.

FIG. 2.

Fig. 1 is a front perspective view of a cosmetic dispenser embodying my new design, viewed from slightly above;

Fig. 2 is a rear perspective view thereof, viewed from slightly below.

The undisclosed end of the dispenser is a mirror image of the end shown.

I claim:

The ornamental design for a cosmetic dispenser, substantially as shown and described.
